(57) **CLAIM**

The ornamental design for a vehicle rear upper bumper, as shown and described.

DESCRIPTION

FIG. 1 is a front and left side perspective view of a vehicle rear upper bumper showing my new design;

FIG. 2 is a front view thereof;

FIG. 3 is a left side elevational view thereof, the right side elevational view being substantially a mirror image and omitted; and,

FIG. 4 is a top view thereof.

The broken lines shown in the drawings depict portions of the vehicle rear upper bumper that form no part of the claimed design.
